CAP FOR A PRESSURIZED FOAM DISPENSER

Adolph J. Wegmann, Glen Cove, N. Y., assignor to Scovill Manufacturing Company, Waterbury, Conn., a corporation of Connecticut

Application April 26, 1956, Serial No. 41,221

Term of patent 7 years

(Cl. D62—2)

FIG. 1.

FIG. 2.

FIG. 4.

FIG. 3.

Fig. 1 is a side elevation of a cap for a pressurized foam dispenser embodying my new design.

Fig. 2 is a top plan view of the cap shown in Fig. 1.

Fig. 3 is a rear elevation of the cap as viewed from the left side of Fig. 1.

Fig. 4 is a front elevation of the cap as viewed from the right side of Fig. 1.

I claim:

The ornamental design for a cap for a pressurized foam dispenser, substantially as shown.
